DESIGN FOR SUSPENDERS OR THE LIKE FOR PERSONAL WEAR

Morris Sachs, Rochester, N. Y., assignor to Hickok
Manufacturing Company, Inc., Rochester,
N. Y., a corporation of New York

Application July 2, 1935, Serial No. 57,501

Term of patent 3½ years

To all whom it may concern:

Be it known that I, Morris Sachs, a citizen of the United States, residing at Rochester, in the county of Monroe and State of New York, have invented a new, original, and ornamental Design for Suspenders or the like for Personal Wear, of which the following is a specification, reference being had to the accompanying drawing, forming part thereof.

In the drawing:

Fig. 1 is a front elevation of a pair of suspenders illustrating my novel design, the detailed illustration of the shoulder straps being continued throughout the length thereof.

Fig. 2 is a fragmentary view of a portion of one of the shoulder straps on an enlarged scale.

Fig. 3 is a transverse sectional view on the line 3—3 of Fig. 2.

I claim:

The ornamental design for suspenders or the like for personal wear, as shown and described.

MORRIS SACHS.
